UNITED STATES PATENT OFFICE

JOHANNES NICOLAUS WILHELMI, OF HAMBURG, GERMANY

METALLIC PILING

Application filed February 28, 1929, Serial No. 343,425, and in Germany February 21, 1928.

This invention relates to metallic piling of the type in which the piles are interconnected by tongues and grooves. Piling of this type, particularly where the tongues and grooves are presented by iron bars riveted to the piles, has various disadvantages, it being found that the rivets break or shear off while the piles are being driven. Moreover, known means for interconnecting the piles consisting of a single tongue and a single mating groove are not satisfactory, for the reason that there is no reciprocal guiding of the interlocking elements, and the piles are liable to separate. Interconnecting means are known in which the tongue and groove are conformably shaped to provide for guiding, the tongue and groove being, for instance, of circular cross section. Such connections suffer from the drawback that they tend to open out, so that the piles jam one another and therefore impede or render pile driving difficult.

The disadvantages mentioned are avoided by the invention according to which there are formed on each longitudinal edge of each pile a groove and a tongue together forming half of a connection and disposed at approximately right-angles to another and engageable with a corresponding tongue and groove formed on the adjacent edge of the adjacent pile. Since, as a rule, the lock or connection is not arranged in the central plane of the piling but on the outer face of the same, it is advisable to arrange the groove and tongue on one side of the pile in such wise that a structure comprising a plurality of interconnected piles presents no projecting parts on the outer face. Since there is formed on each edge of each pile a groove as well as a tongue disposed at right-angles to one another, there is obtained a double connection, that is to say, a connection in the longitudinal direction of the piling as well as transversely thereto.

In the accompanying drawings Fig. 1 is a cross-section of the cooperative edges of adjacent piles, the edges being separated from one another, constituting an open connection, and Fig. 2 is a similar view showing the two members engaging one another to form a

closed connection or lock. Figs. 3 and 4 illustrate two ways of using the invention for constituting pile planking.

In the construction shown in Fig. 1 the groove *a* is approximately square in cross-section, one wall being formed by the tongue *b*. The tongue *d* and groove *c* on the adjacent edge of the adjacent pile form the mating half of the connection and are shaped to engage *a* and *b*, Fig. 3. It will be understood from Fig. 2 that the mating elements *a* and *d* are at right-angles to one another, as are the elements *b* and *c*, thus forming a rigid connection. The groove *a* of one pile and the tongue *d* of the cooperating pile prevent any yielding or distortion of the two piles in a direction at right-angles to the piling, while the tongue *b* and the groove *c* prevent separation of the two piles in the direction of the piling, so that rupture of the wall in both directions is avoided.

The disposition of the grooves and tongues is such that when the piles are interconnected they present a smooth outer surface which facilitates the application of bracings or the like.

As shown in Fig. 1 the tongue *b* of one pile is flush with the outer face of said pile and is of approximately trapezoidal cross-section, the base of the trapezoid being next to the outer face of said pile, while the tongue *d* of the other pile is joggled with respect to the outer face of said second pile and is of approximately square cross-section.

It will be seen from Fig. 4 that it is not absolutely necessary to arrange the connection or lock on the back of the piling, the connection or lock being arranged on any part of the piling as may be found convenient.

The double connection is not only of advantage for restraining the piles in all directions; the tortuous nature of the contacting faces also improves and increases the water-tightness of the complete piling. The shaping of the grooves and tongues as described and shown has also the advantage of avoiding all jamming and blocking while the piles are being driven, thereby eliminating the contingency of a driven pile be-

ing torn when an adjacent pile is being driven. Twisting and distortion during driving, as have frequently occurred heretofore, are also eliminated.

- 5 Having now particularly described and ascertained the nature of my said invention and in what manner the same is to be performed, I declare that what I claim is:—
- Metallic piling comprising a plurality of
10 unitary, cooperating piles, each of which piles is provided at each end with offset tongues and grooves for connection with cooperating parts of the adjacent piles, the tongue of one of the two cooperating pile
15 ends being flush with the outer face of the pile and of substantially trapezoidal cross section, the base of the trapezoid comprising the outer face of the said tongue, the corresponding tongue of the cooperating pile
20 forming part of the second half of the connection and being inset with respect to the outer face of the pile on which it is formed and of approximately square cross section, to such an extent that the inner face is slightly
25 oblique to correspond to the trapezoidal shape of the first-named tongue, the grooves of each pile being shaped to fit the tongue of the adjacent pile, and a flap on one of the piles cooperating with the said trapezoidal tongue
30 to prevent lateral movement of the piles relative to each other.

In testimony whereof I have signed my name to this specification.

JOHANNES NICOLAUS WILHELM.
